UNITED STATES PATENT OFFICE.

CHRIST ANDERSON, OF TWO HARBORS, MINNESOTA.

DOOR OPERATING AND CONTROLLING MECHANISM.

1,145,736.

Specification of Letters Patent.

Patented July 6, 1915.

Application filed December 9, 1914. Serial No. 876,316.

To all whom it may concern:

Be it known that I, CHRIST ANDERSON, a citizen of the United States, residing at Two Harbors, in the county of Lake and State 5 of Minnesota, have invented certain new and useful Improvements in Door Operating and Controlling Mechanisms, of which the following is a specification, reference being had therein to the accompanying drawing.

10 My invention relates to improvements in door operating and controlling mechanisms the primary object of which is to provide a simple and inexpensive device whereby a door may be opened or closed from any desired point apart from the door itself.

Another object of the present improvement is to construct a device which is adapted to be operated at a point any desired distance from the door to which it is applied 20 and unlatch the said door and either open it or close it.

25 My present invention is applicable to nearly any form of swinging door, yet it is intended to be applied more particularly to doors such as are found in depots, hotels, or public buildings where many people are passing out, and is especially adapted for the use of those persons who are heavily burdened, such as with two satchels or 30 bundles of any sort where the turning of a knob to unlatch the door and push it, frequently occasions the resting of one or both burdens.

The device may be used to good advantage 35 in connection with furnace doors where it is desired to keep the door open but a very short time, such as for instance, while throwing in a shovel full of coal.

Other objects and advantages of the present 40 improvement will be more particularly pointed out in the following description and drawings in which—

45 Figure 1 is a side elevation of a fragmental portion of my device showing a part of the door and door frame in section. Fig. 2 is a top plan view of the door and door operating portion of the device showing a part of the door frame in section.

50 Referring now to the drawings in detail in which like reference numerals designate similar parts, 1 represents the door shown in Fig. 1 in closed position and adjacent the side of the door frame 2. The door in this figure is shown latched and a catch bolt 55 3 of the lock is shown mounted upon or within the door. It is not considered neces-

sary to illustrate any particular form of lock, as it is well known that there are a great many varieties of door locks comprising a horizontally reciprocal bolt which 60 springs into an opening within the door frame when the door is closed. In the illustration here the opening in the door frame into which the reciprocal bolt 3 of the door 1 moves is numbered 4 and is protected in 65 the door frame by the usual escutcheon plate 5.

Referring now to my improved operating and controlling device, a horizontally extending bracket plate 6 is provided which 70 is made preferably of metal and formed with a base portion 7 arranged at right angles thereto and integral therewith. This portion provides means whereby the bracket is securely fixed to the door frame 2 by 75 means of screws 8. The portion 7 is arranged so as to be directly opposite the recess 4 in the door frame into which the bolt 3 of the door lock reciprocates. A tubular housing 9 of either round or rectangular 80 cross section is carried by and integral with the base portion 7 of the bracket 6. This tubular portion extends on each side of the base portion 7, the inner end of which tubular portion communicates with the recess 4 85 in the door frame. A trip bolt 10 is reciprocally mounted within this tubular housing 9. The means for reciprocating the trip bolt 10 comprises shear arms 11 and 12 which are pivotally connected at 13. The other end 90 of the arm 11 is pivotally connected to the trip bolt 10 and the other end of the shear arm 12 is pivotally mounted upon the bracket plate 6 at the point 14.

The means for tripping the bolt consists 95 of an operating device apart from the door and comprises a rod 17 which is pivotally mounted upon the shear arm 12 at the point 16, the lower end of the rod 17 being pivot- 100 ed to a vertically reciprocal rod 18 at the point 61. The lower end of the rod 18 is designed to extend down through the floor 20 and is pivotally connected at 21 to the arm 22 of a bell-crank lever 23. The op- 105 posite arm 24 of this bell-crank lever 23 is pivotally connected at 25 to a rod 26. The bell-crank 23 is pivotally suspended in a suitable depending bracket 27 securely at- 110 tached to the under side of the floor 20. The opposite end of the rod 26 is pivotally at- tached at the point 28 to the arm 29 of a sec- 115 ond bell-crank 30 which is pivotally sus-

2

pended at 31 upon a depending bracket 32, also attached to the under side of the floor 20. This bracket may be placed at any desired distance from the door and door frame 5 and the rod 26 may be of any desired length and, in fact, a wire line or chain might be used in place of the rod and made to lead over suitable pulleys and thereby connect this bell-crank directly to the end of the rod

- 10 18. The other arm 33 of the bell-crank 30 is pivotally connected at 34 to the lower end of a pitman 35 which extends upwardly through a suitable hole 36 in the floor 20. This pitman extends above the floor a sufficient distance to be readily accessible to the foot of the operator for depressing the same and thereby release the latch 3 as will be more fully hereinafter pointed out and also open the door by means hereinafter to be described.

15 A hasp 37 is pivotally mounted at 38 adjacent the upward protruding pitman 35 whereby the pitman may be retained in its depressed position when desired by slipping 25 the end of the hasp over the end of the pitman after the latter has been depressed and this operation may be readily accomplished by the otherwise unoccupied foot of the operator.

- 20 30. The means for opening the door comprises a mechanism attached to the upper end of the vertically reciprocal rod 18. The upper end 39 of this rod 18 is pivotally connected at 40 to the arm 41 of a bell-crank 42 which 35 is pivotally supported at 43 upon a bracket 44 securely fixed to the inner face of the door frame 2 and adjacent the upper end of the door 1 for the purpose hereinafter to be described. The opposite arm 45 of the bell-crank 42 is pivotally connected at 46 to a horizontally reciprocal rod 47 which extends through a suitable hole 48 in the door frame to a point approximately opposite the middle of the door. At this point the end of 45 the rod 47 is pivotally and longitudinally loosely connected to the short arm 49 of another bell-crank 50 which is pivotally mounted in any suitable manner at 51 upon or within the horizontal wall or cap of the 50 door frame. In the present case I have illustrated it pivotally mounted within a recess 52 formed for the purpose.

55 The long arm 53 of the bell-crank 50 extends horizontally to a point approximately opposite the hinge of the door where it is pivotally connected as at 54 to one end of a rod 55, the opposite end of which rod is pivotally connected at 56 to the upper edge of the door 1. The point of connection with the door and the rod 57 I prefer to be the center of the door as this point of connection will give the most desirable motion to the door when operated upon.

60 The connection of the rod 47 with the arm 49 of the bell-crank 50 is made flexible or

loose longitudinally the rod by means of a pivotal pin 57 being mounted within a horizontal slot 58 formed within the end of the rod 47. A flexible connection is provided at this point for the purpose of allowing 70 the latch releasing mechanism to work and release the latch before the door operating mechanism is at all operated. In other words, due to this arrangement the entire mechanism except the bell-crank 50 and rod 75 55 which are connected to the door may operate slightly before any force is applied to the door, thus permitting the bolt 10 to be thrust inwardly sufficient to force out the bolt 3 from its engagement with the door 80 frame and thereby unlatching the door just prior to its being acted upon by the continued movement of the rod 47 when it engages the crank 50 and through the mechanism hereinbefore described act upon the 85 door to open it.

90 The means for closing the door after the foot of the operator has been released from the pitman 34 comprises a spiral spring 59 which is attached in any desired manner to the rod 18 as by means of the member 60 which is here illustrated as being pivotally attached at the point 61. The other end of the spring 59 may be attached to the bracket 44 by means of a suitable hook 62 or any 95 other convenient means. The spring 59 being normally contracted, it is evident that the mechanism will thus be held in the inactive position illustrated in the drawings, but when pressure is applied to the pitman 35 100 and the door then unlatched and swung open against the spring 59 as soon as the pressure is removed, the said spring will restore the mechanism and door to its original position. Upon the return motion the 105 momentum of the door together with the spring will always be sufficient to perform the final act of closing, at least sufficient for the bolt 3 to assume its proper position in the recess 4 of the door frame.

110 As is evident, the entire mechanism is designed to be installed within the wall of the building adjacent the door frame, and entirely out of sight except the rod 55, the upper end of the pitman 35 and the hasp 115 for the same.

115 It is apparent from the above description that I have provided a device which by one movement of the foot or hand of the operator (if the pitman 35 were sufficiently extended) the door may be unlatched and swung open from a point any desired distance apart from the door.

120 Having thus fully described my invention what I claim and desire to secure by Letters Patent is:

125 1. A door controlling and operating device comprising a right angular bracket having one of its legs secured to the door-frame, said leg having a tubular portion ex- 130

- tending through the door-frame and having its inner end adjacent the latch bolt of the door, a member reciprocally mounted within the said tubular portion, two levers pivoted together, one end of one lever pivoted to the reciprocating member and one end of the other lever pivoted to the leg of the right angular brace extending at right angles to the door-frame, a vertically reciprocating rod mounted adjacent the door-frame, a link having one end pivoted to one of the first-mentioned levers and its other end pivoted to the vertically movable rod, means for raising and lowering the vertically movable rod and thereby pushing the reciprocal member in and drawing it out of the tubular portion of the right angular brace for the purpose described, and means carried by the upper end of the vertically 20 movable rod for opening the door.
2. A door opening and controlling device comprising a vertically movable rod adjacent the door-frame and extending parallel thereto, means connected to the lower end 25 of the said rod for moving it vertically, means connected to and actuated by the vertically movable rod for releasing the latch bolt of the door, means for opening the door connected to the upper end of the vertically 30 movable rod, said means comprising a bell crank lever pivotally mounted upon the door-frame and having one of its ends connected to the vertically movable rod, a link 35 extending parallel to the upper edge of the door and having one end pivotally connected to the bell crank lever, the other end of the said longitudinally extending lever having an elongated slot therein, a second bell 40 crank lever mounted adjacent the upper edge of the door one arm of the bell crank lever considerably shorter than the other arm, the short arm of the said bell crank lever having a lug slidably mounted within the slot of the longitudinal lever, another 45 link having one end pivotally connected to the longer arm of the last-mentioned bell crank lever and its other end pivotally connected to the top edge of the door at approximately the center thereof, the door unlatching mechanism operated in advance of the opening mechanism due to the play in the longitudinal slot in the end of the lever 50 extending longitudinal and parallel to the top of the door.
- 50 unlatching mechanism operated in advance of the opening mechanism due to the play in the longitudinal slot in the end of the lever extending longitudinal and parallel to the top of the door.
3. A door controlling and operating device comprising a right angular bracket having one of its legs secured to the door frame, said leg having a tubular portion extending through the door-frame and having its inner end adjacent the latch bolt of the door, a member reciprocally mounted within the said tubular portion, two levers pivoted together, one end of one lever pivoted to the reciprocating member and one end of the other lever pivoted to the leg of the right angular brace extending at right angles to the door-frame, a vertically reciprocating rod mounted adjacent the door frame, a link having one end pivoted to the vertically movable rod, means for raising and lowering the vertically movable rod thereby pushing the reciprocal member in and drawing it out of the tubular portion of the right angular brace for the purpose described, means for opening the door connected to the upper end of the vertically movable rod, a link 70 extending parallel to the upper edge of the door and having one end pivotally connected to the bell crank lever, the other end of the said longitudinally extending lever having an elongated slot therein, a second bell 75 crank lever mounted adjacent the upper edge of the door one arm of the bell crank lever considerably shorter than the other arm, the short arm of the said bell crank lever having a lug slidably mounted within the slot of the longitudinal lever, another link having one end pivotally connected to the longer arm of the last-mentioned bell 80 crank lever and its other end pivotally connected to the top edge of the door at approximately the center thereof, the door unlatching mechanism operated in advance of the opening mechanism due to the play in the longitudinal slot in the end of the lever 85 extending longitudinal and parallel to the top of the door.
- In testimony whereof I hereunto affix my signature in the presence of two witnesses.
- CHRIST ANDERSON.
